UNITED STATES PATENT OFFICE.

DANIEL W. MCNEIL, OF CINCINNATI, OHIO, ASSIGNOR TO THE JOHN DOUGLAS COMPANY, OF CINCINNATI, OHIO, A CORPORATION OF OHIO.

SPRING-HINGE.

No. 902,596.

Specification of Letters Patent.

Patented Nov. 3, 1908.

Application filed November 25, 1907. Serial No. 403,581.

To all whom it may concern:

Be it known that I, DANIEL W. MCNEIL, a citizen of the United States of America, and resident of Cincinnati, county of Hamilton, State of Ohio, have invented certain new and useful Improvements in Spring-Hinges, of which the following is a specification.

My invention relates to spring hinges, especially those which are used for holding water-closet seats normally elevated at their forward ends at angles to the bowls.

The object of my invention is a spring hinge which will hold the seat raised from the bowl normally at a uniform angle, but one of small degree, and which is simple in construction and easily fixed in place.

Referring to the accompanying drawings, Figure 1 is a side elevation of a bowl, a seat and a flushing valve, provided with a hinge, embodying my invention. Fig. 2 is a plan view of a hinge embodying my invention upon a somewhat enlarged scale. Fig. 3 is a view similar to Fig. 2 but showing the journal tube in section. Fig. 4 is a sectional view taken upon line x—x of Fig. 3, but upon an enlarged scale.

Bowl, A, has secured at its rear two brackets with cylindrical bearings, a, a', between which is held the tube, b, upon which leaf, B, of the hinge is journaled by means of collars, b', b''. The leaf, B, is secured to the underside of the seat, C, at its rear. Journal bearing, a', has formed integral with it a plug, a'', which has a vertical slot, a''', cut through it. A flat bar, D, of resilient metal is secured in the slot, a''', by means of a set-screw, a'', extends through the center of the journal tube, b, and has secured upon its opposite end a bell crank lever, E, one of whose arms, e, is

connected by links, f, f', to the push rod, F, 40 of the flush valve, and the other of whose arms, e', is positioned to take under the rear edge of the seat, C, the parts being so adjusted that in the normal position of the bar, D, the arm, e', holds the seat, C, at a slight 45 angle to the bowl. The leaf, B, is provided with a lug, b'', against the underside of which the arm, e', bears. When the arm, e', of the bell crank lever, E, is depressed, the bar, D, is under torsion. As soon as the pressure on 50 the arm, e', is released, the torsion of the metal in the bar, D, will bring the bar back to its normal position, such as shown in Fig. 1.

What I claim is:

1. The combination of a closet bowl, a seat, 55 means of hinging the seat to the bowl, a bearing upon the bowl, a bar, a means of securing the bar to the bearing so as to limit the rotation of the bar in the bearing and a holding arm secured to the free end of the bar and 60 contacting the seat to hold it normally in a raised position.

2. The combination of a bowl, a tube, means of mounting the tube upon the bowl, a leaf with collars journaled upon the tube, a 65 seat secured to the leaf, a bar within the tube, means of securing the bar at one end against rotation, a bell crank lever secured upon the opposite end of the bar and having one of its arms contacting the seat to hold it 70 normally in a raised position and the other arm being adapted to be secured to a flushing device.

DANIEL W. MCNEIL.
